UNITED STATES PATENT OFFICE.

ERNST OSCAR NEBEL, OF PHILADELPHIA, PENNSYLVANIA.

PROCESS OF MANUFACTURING FULL-FASHIONED HOSIERY.

Application filed March 15, 1927. Serial No. 175,546.

This invention relates to the manufacture of full-fashioned hosiery, and has for its principal object the formation of full-fashioned hosiery blanks on a single knitting machine, which eliminates the well known "topping" operation.

The process involved in manufacturing stockings according to the principles of my invention will be fully disclosed hereinafter, reference being had to the accompanying drawings, of which:

Fig. 1 shows the lower leg and foot portions of a stocking blank produced according to the principles of my invention;

Fig. 2 shows a plurality of heel tabs formed in a continuous strip;

Figs. 3 and 4 illustrate a pair of heel tabs removed from the strip shown in Fig. 2;

Fig. 5 shows the blank of Fig. 1, split at desired points and the heel tabs of Figs. 3 and 4, inserted and secured to the split blank;

Fig. 6 illustrates the stocking in its completed form.

Fig. 7 is a diagrammatic view illustrating the manner of forming guide lines at each side of the stocking blank; and

Fig. 8 illustrates diagrammatically the stitches of the fabric at and around the points where the guide lines are formed in the blank.

My invention comprises the formation of the welt, the upper leg portion, the narrowed calf portion, and a part of the spliced heel and instep portions of a stocking blank in the usual manner, on the usual and well known types of flat knitting machines known to the art as "leggers". These portions of the stocking blank are designated by the reference characters 1, 2, 3 and 4 respectively.

The usual and well known operations which are employed in the formation of full-fashioned stocking blanks are performed in forming the stocking blank according to the principles of my present invention, including the upper portion 5 of the high splice heel and down to the line 6, at which point, under the usual practice the knitting of the instep portion 7 is discontinued and the formation of integral heel tabs is carried on, after which the blank is removed from the "legger" and passes through the "topping" operation, wherein the instep stitches and the inner selvage edges of the depending heel tabs are placed

on a "topping bar" in a manner to be transferred to the "footer", a machine which completes the stocking blank.

The disadvantages of this "topping" operation are well known to those familiar with the art. During this operation the percentage of "factory seconds" is greatly increased, due to dropping stitches, misplacing stitches on the quills of the topping bar and many other forms of misapplication.

The formation of the leg and foot portions on separate machines also has many disadvantages, such as the formation of different textures in the two parts of the stocking, due to a slight difference in the yarns employed, a variation in the tension of the two yarns on the separate machines, and the mechanical operations of the separate machines themselves.

According to my invention, these objections are eliminated by forming the blank from welt to toe on a single machine, with a single yarn under a uniform tension.

When the point 6 is reached, in the process of manufacture according to the principles of my invention, I form in succession a loose course of stitches 8, two successive courses of regular stitches 9, 9, and a second loose course 10 from the selvage edges 11 and 12 of the blank inward to the lines 13 and 13^a respectively, which divides the reinforced portions 14, 14 of the blank from the non-reinforced instep portion 7 thereof. The continuations of the loose courses 8 and 10 and the regular courses 9, 9 across the instep portion 7 are not loose but are formed in a regular manner. The formation of the remainder of the foot portion 15 of the stocking blank then progresses in the usual and well known manner.

Referring to Figs. 7 and 8, when the knitting progresses to the line 6, the body thread *x* is thereafter carried entirely across the stocking blank from the selvage 12 to the selvage 11 thereof, the reinforcing thread *y* is carried from the selvage 12 to the limit line 13, and the reinforcing thread *y*¹ at the opposite side of the blank is carried from the limit line 13^a, adjacent the selvage 11, to the said selvage edge 11. The body thread *x* and the reinforcing thread *y* are then knit together in a manner to form the loose course 8, from the selvage 12 to the limit line 13, the body thread *x* between the limit lines 13, 13^a being knit into a course of regular stitches 7^a, and between the limit line 13^a and the

selvage 11 a course of regular reinforced stitches is also formed.

The body thread x is then carried across the blank in a reverse direction from the selvage edge 11 to the limit line 13 (Fig. 7). Between the selvage edge 11 and the limit line 13^a, on this stroke, the loose course 8 at the opposite side of the blank adjacent the selvage 11 is formed. The stitches 7^b across the instep portion 7 on this stroke are regularly formed. In place of the body thread x and the reinforcing thread y being knit together between the limit line 13 and the selvage 12, on this stroke, the thread y is employed alone to form the first of the intermediate regular guide line courses 9 between the said limit line 13 and the selvage 12.

The body thread x is then moved from the line 13 to the line 13^a to form a course of regular stitches 7^c, between these two limit lines only. The reinforcing thread y , during this movement of the body thread x , is moved from the selvage 12 to the limit line 13 to form the second course of plain regularly formed guide line stitches 9 adjacent the selvage 12; and the reinforcing thread y^1 is moved from the guide line 13^a to the selvage 11 to form the first course of regular guide line stitches 9 adjacent the selvage 11.

The body thread x is then moved from the guide line 13^a to the selvage 12 and the reinforcing thread y is moved in a similar direction from the guide line 13 to the selvage 12, the body thread x between the guide lines 13^a and 13 is then knit into a course of regular stitches 7^d and between the guide line 13 and the selvage 12 the body thread x and the reinforcing thread y are concurrently knit into the loose course 10, between the said guide line 13 and the selvage 12. The reinforcing thread y^1 at the opposite side of the blank at the same time has been moved from the selvage 11 to the guide line 13^a and knit into the second regularly formed course of guide line stitches 9 between the said guide line 13^a and the adjacent selvage 11.

The body yarn x is then moved in a direction from the selvage 12 to the selvage 11; the reinforcing thread y is similarly moved from the selvage 12 to the limit line 13 to form together a course of regular reinforced stitches therebetween, and the reinforcing thread y^1 is moved from the limit line 13^a to the selvage 11 to form together with the body thread x the loose course 10, at the side of the blank adjacent the selvage 11; the body thread x between the limit lines 13 and 13^a forming a course of regular non-reinforced stitches 7^e.

From this point on the body thread x and the two reinforcing threads y and y^1 are passed alternately back and forth within

their regular prescribed limits for completing the foot portion 15 of the stocking blank.

Upon referring to Fig. 8, it will be noted that the ends of the instep courses 7^b and 7^c and the ends of the guide line courses 9, 9 adjacent the limit line 13 are in no way connected to each other, which forms a selvage edged hole 30 in the blank. This arrangement permits the stocking blank to be split along the guide lines 9, 9 inward to the hole 30 without causing any loose end to be formed in the stocking blank, thus no "runs" in the stocking when worn. The body thread x is not cut in forming the split in the blank, thus no loose ends occur in this thread and the thread y , forming the guide line courses 9, 9, when cut is securely tied into the fabric adjacent the split by the uncut body thread x , in the loose courses 8 and 10 respectively, thus no "runs" can occur due to the splitting of the blank. This condition is identical at each side of the stocking blank.

The operation above described can be accomplished on any ordinary flat knitting machine, and the movements of the thread guides to carry the respective threads across the blank, as noted, can be regulated; and the actuation of the needle bar to produce the loose courses of stitches at the specified points can be effected by any ordinary skilled mechanic familiar with machines of this character.

On another machine of any desired type, I knit in strip form (Fig. 2) a plurality of heel tabs 20, 20 and across the strip at stated intervals I form loose courses 21 and 22 which form division lines between the individual heel tabs 20 and the adjacent connecting portions 23 of the continuous strip.

The heel tabs 20 are narrowed in the usual manner as illustrated at 24, and the interconnecting portions 23 of the strip are widened as at 35 to compensate for the difference in the width of the heel tabs at the lines 21 and 22.

The heel tabs 20, 20 are separated, by cutting or otherwise, at a point within the connecting portions 23 of the strip. The fabric is then raveled to the line or loose course 21 (Figs. 3 and 4).

The blank illustrated in Fig. 1 is then split along the guide line formed by the regularly formed courses 9, 9, intermediate the loose courses 8 and 10, on each side of the blank, from the respective selvage edges 11 and 12 inward to the selvage edged holes 30, 30 formed on the limit lines 13 and 13^a respectively. The loose course 8 of the blank, on each side thereof, is then joined with the loose course 21 of one of the heel tabs 20 and the two loose courses being thereupon connected by means of looping or sewing, as illustrated at 26 in Fig. 5, by any of the well known processes. The selvage edge 25

of the heel tab 20 is then looped or otherwise secured to the loose course 10 of the foot portion of the stocking blank, as clearly illustrated at 27 in Fig. 5. The cut ends 5 of the fabric strip extending beyond the loose courses 22 of the heel tabs 20, 20 are raveled to the said loose courses 22.

The stocking blank is now ready to be joined by looping or otherwise securing the 10 selvage edges 11 and 12 of the blank together from the toe line 28 to the top line of the welt of the stocking. During this operation, the selvage edges 29, 29 and the loose courses 22, 22 of the oppositely disposed heel tabs 20, 20 are likewise joined to form the complete stocking as illustrated in Fig. 6. Obviously the toe tab 30 (Figs. 3 and 5) is raveled or otherwise removed down to the usual toe line loose course 28 before 20 the selvage edges of the stocking are joined.

Throughout the specification I have described my process of manufacture as being carried out on the well known "flat" type of knitting machine, but obviously the operation 25 could be successfully performed on what is known as a "circular oscillating" type of knitting machine which is adapted to produce full-fashioned flat hosiery blanks, without departing from the essential features of the invention as above described.

I claim:

1. A process of producing full-fashioned hosiery, comprising the formation of a flat stocking blank throughout its entire length 25 on one full-fashioned hosiery knitting machine; reinforcing the blank adjacent its opposite edges at the foot and heel portions of the blank; forming successively a loose course of stitches, a pair of regular courses 40 of stitches and a second loose course of stitches transversely of said reinforced portion at the line of division between the said heel and foot portions of the blank, the connecting part of said successively formed 45 courses which extends across the instep portion of the blank being of regular stitches; forming heel tabs independent of the said blank in the form of a continuous selvage edged strip; forming loose courses of 50 stitches transversely of and at predetermined intervals throughout the length of the strip, whereby the said strip is divided alternately into individual heel tabs and sections of cutting fabric therebetween; cutting 55 the strip intermediate the loose courses at the ends of the individual tabs; raveling the cut fabric down to the said loose courses; splitting the blank inward from each of the outer edges thereof along the central regularly formed courses of stitches located 60 between the said loose course of stitches in each side of the stocking blank; inserting one of said heel tabs in each side of said blank within the said splits; and securing the loose course of one end of the inserted

heel tab to one of the respective adjacent loose course edges formed by the said splitting of the said blank; securing the other loose course edge of said split to an adjacent selvage edge of said inserted heel tab; and 70 securing the outer edges of said completed blank together, to form a complete stocking.

2. A process of producing full-fashioned hosiery, comprising the formation of a flat stocking blank throughout its entire length 75 on a single full-fashioned hosiery knitting machine; including the formation of a reinforced high spliced heel and reinforced foot portion and a non-reinforced instep portion; forming a guide line of stitches in 80 said reinforced portion of the blank at each side of said blank; forming a selvage edged hole in the blank at the inner end of each guide line; forming heel tabs independent 85 of the said blank; splitting the blank inward from each of the outer edges thereof on said guide lines to the said selvage edged holes; inserting one of said heel tabs in each side of said blank within the said splits; and securing each of a pair of adjacent 90 edges of each inserted heel tab to the respective adjacent edges formed by the said splitting of the said blank.

3. A process of producing full-fashioned hosiery, comprising the formation of a flat 95 stocking blank throughout its entire length on a single full-fashioned hosiery knitting machine; reinforcing the blank adjacent its opposite edges from the toe to a point intermediate the toe and the narrowed calf of the blank; forming a pair of regular courses 100 of stitches in the reinforced portion of the blank at each side of said blank adapted to act as guide lines; forming a selvage edged hole in the fabric at the inner end of said guide line; forming a course of loose 105 stitches at each side of and parallel with each pair of said guide line regular courses; forming heel tabs independent of the said blank; splitting the blank inward from each 110 of the outer edges thereof along said guide line courses to the selvage edged hole at the inner end thereof; inserting one of said heel tabs in each side of said blank within the said splits; and securing each of a pair of adjacent edges of each inserted heel tab to the respective loose courses comprising the 115 adjacent edges formed by the said splitting of the said blank.

4. A process of producing full-fashioned hosiery, comprising the formation of a flat stocking blank throughout its entire length 120 on a single flat knitting machine and the employment of a single body thread throughout the formation of the entire blank, wherein the said body thread is first fed to all the needle wales used in the formation of the blank from selvage to selvage thereof for a given number of courses, after 125 which a reinforcing thread is fed to a given 130

number of needle wales located adjacent each selvage edge of the blank together with the said body thread for a given number of courses to form a heel reinforced area in each 5 side of the blank, for the next course of stitches to be formed the body thread is fed from one selvage edge of the blank to the needle wale immediately adjacent the inner edge of the reinforced area at the opposite 10 side of the blank the reinforcing thread operating in this reinforced area alone forming the corresponding course of stitches therein and being separated from the stitches formed by the body thread, the body 15 thread is then fed in a reverse direction to the needle wale adjacent the inner edge of the reinforced area at the first mentioned side of the blank and the reinforcing thread in this area alone forming the corresponding 20 course of stitches therein being separated from the stitches formed by the body thread, the body thread is then fed in an opposite direction to the oppositely disposed selvage edge of the blank, then back and forth across the entire width of the blank 25 for the remainder of the courses necessary to complete the blank, the said manipulation of the threads forming a cutting line in each reinforced area composed solely of 30 the reinforcing threads operating in the respective reinforced areas and forming a selvage edged hole at the inner end of each cutting line whereby the cutting of the body thread at the inner end of each cutting line 35 is obviated.

5. A process of producing full-fashioned hosiery, comprising the formation of a flat stocking blank throughout its entire length on a single flat knitting machine and the 40 employment of a single body thread throughout the formation of the entire blank, wherein the said body thread is first fed to all the needle wales used in the for-

mation of the blank from selvage to selvage thereof for a given number of courses, after 45 which a reinforcing thread is fed to a given number of needle wales located adjacent each selvage edge of the blank together with the said body thread for a given number of courses to form a heel reinforced area 50 in each side of the blank, for the next course of stitches to be formed the body thread is fed from one selvage edge of the blank to the needle wale immediately adjacent the inner edge of the reinforced area at the opposite side of the blank the reinforcing thread operating in this reinforced area alone forming the corresponding course of 55 stitches therein and being separated from the stitches formed by the body thread, the body thread is then fed in a reverse direction to the needle wale adjacent the inner edge of the reinforced area at the first mentioned side of the blank and the reinforcing thread in this area alone forming the corresponding course of stitches therein being separated from the stitches formed by the body thread, the body 60 thread is then fed in a reverse direction to the needle wale adjacent the inner edge of the reinforced area at the first mentioned side of the blank and the reinforcing thread in this area alone forming the corresponding course of stitches therein being separated from the stitches formed by the body thread, the body 65 thread is then fed in an opposite direction to the oppositely disposed selvage edge of the blank, then back and forth across the entire width of the blank 70 for the remainder of the courses necessary to complete the blank, the said manipulation of the threads forming a cutting line in each reinforced area composed solely 75 of the reinforcing threads operating in the respective reinforced areas and forming a selvage edged hole at the inner end of each cutting line whereby the cutting of the body thread at the inner end of each cutting line 80 is obviated, forming heel tabs independent of said blank, splitting the blank on said cutting lines, and attaching adjacent edges of said tabs to the respective edges formed by the splitting of the blank.

ERNST OSCAR NEBEL.
